UNITED STATES PATENT OFFICE.

ERNST G. K. ANDERSON, OF CHICAGO, ILLINOIS, ASSIGNOR TO BENJAMIN ELECTRIC MANUFACTURING COMPANY.

ATTACHMENT-PLUG.

1,225,391.

Specification of Letters Patent.

Patented May 8, 1917.

Application filed April 10, 1913. Serial No. 760,261.

To all whom it may concern:

Be it known that I, ERNST G. K. ANDERSON, a citizen of the United States, residing at Chicago, in the county of Cook and State 5 of Illinois, have invented new and useful Improvements in Attachment-Plugs, of which the following is a full, clear, concise, and exact description, reference being had to the accompanying drawing, forming a 10 part of this specification.

My invention pertains to attachment plugs, and especially relates to the class of plugs known as "separable", *i. e.*, plugs consisting of two readily disengageable members, an outer member and an inner member, of which the outer member is adapted to be inserted into a lamp socket or the like, and the inner member carries binding terminals for receiving the ends of leading-in 15 conductors. It is one of the principal objects of my invention to provide a separable plug of a simple, convenient and efficient construction, in which the threaded contact of the outer member will be rotatable with 20 respect to the remainder thereof.

An attachment plug constructed in accordance with my invention is described, by way of example, in the following specification and shown in the accompanying 30 drawing. The construction shown and described, is, however, only one of those in which my invention may be embodied; and changes may be made therein without exceeding the scope of my invention as defined in the appended claim:

In the drawing:—

Figure 1 is an elevation of the plug;

Fig. 2 is a section taken vertically through the same;

Fig. 3 is a detached side view of the inner contact sleeve of the outer plug member;

Fig. 4 is an inverted plan of the same;

Fig. 5 is a vertical section through the 45 insulating button of the inner member;

Fig. 6 is a view similar to Fig. 5, the section being taken, however, at right angles to that of Fig. 5; and

Fig. 7 is a detached inverted plan of the 50 insulating button of the outer plug member.

Like reference characters refer to like parts throughout the following specification and the several figures of the accompanying drawing.

55 As has been said, the plug consists of an

outer member adapted to be secured into a wall socket, lamp socket or the like, and an inner member, adapted to make electrical connections with the outer member, and carrying binding terminals for receiving leading-in-wires. The outer member comprises an insulating button 10 having an axial passage formed therethrough, through which passes a rivet 11, the outer end of which is flanged, at 12, to form the outer center contact of the outer plug portion. The inner end of the rivet 11 is flanged over, at 13, and serves to secure in place the seat portion 14 of a V shaped metallic strip, the end 15 of which forms the inner center contact of 60 the outer plug portion. The strip 14, 15 is flexible and is reinforced by a spiral spring 16 disposed between the end 15 and the rivet 11, the button 10 being formed with a recess 17 for accommodating this spring. The 65 button 10 is reduced at 18 to receive a metallic sleeve 19, which is secured in place thereon by means of tongues 20 which are stamped out of the sleeve 19 and project into recesses 21 in the button. It will be 70 seen that the sleeve 19 may be passed over the reduced portion of the button, the tongues 20 springing out to permit this. When, however, the tongues 20 have entered the recesses 21, the sleeve cannot be removed 75 again. The sleeve 19 is formed with an outwardly extending flange 22 at its outer end, which flange engages against the shoulder formed by reducing the portion 18 at the 80 button. It will be 85 seen that the sleeve 19 may be passed over the reduced portion of the button, the tongues 20 springing out to permit this. When, however, the tongues 20 have entered the recesses 21, the sleeve cannot be removed again. The sleeve 19 is formed with an outwardly extending flange 22 at its outer end, which flange engages against the shoulder formed by reducing the portion 18 at the 90 button.

Rotatably mounted on the sleeve 19, so as to make electrical connection therewith, is the threaded contact 23 of the outer plug portion. The threaded contact passes through, and is flanged over beyond, an insulating thumb ring 24 by means of which the contact may be manipulated in screwing the plug into or out of a socket. The sleeve 19 is formed with a flange 25, at its inner end, which engages against the inner end of 95 the threaded contact 23, and thus prevents the latter from being withdrawn lengthwise, while permitting it to rotate freely with respect to the sleeve 19.

The sleeve 19 is formed with a plurality 100 of slots 26 extending from its inner edge outward, whereby a certain resiliency, in a radial direction, is given. The sleeve is further formed with an inwardly extending circumferential bead 27, which, when the 110

inner plug member is in place in the outer plug member, is engaged by a corresponding circumferential groove 28 formed in a sleeve contact 29, which forms part of the inner plug member. The sleeve contact 29 is formed with a reduced and screw-threaded collar 30 at its inner end; and it carries, at its outer end, an insulating button 31. This button rests upon the shoulder 10 formed by the reduced collar 30 and is retained in place by the upper edge of the sleeve contact 29, which is spun inward somewhat, to that end. The button 31 is of a substantially hemispherical shape at its upper part and enters a correspondingly shaped cavity 32 formed in the inner face of the button 10 of the outer plug member, so that the center contact of the inner plug member, to be described below, can engage the center contact 15 of the outer plug member.

The button 31 of the inner plug member is formed, at the center of its upper part, with a cavity 33 having two holes 34 communicating therewith and with the lower end of the button. In the cavity 33 lies a binding terminal plate 35 having lugs 36 which are bent downward to pass through the holes 34, these lugs being bent over at their ends so as to retain the plate 35 in position. The plate 35 has a screw threaded hole through which passes a screw 37, which also passes through a dished center contact 38. Communicating with the chamber 33, is a passage 39, through which a lead conductor may be brought to the plate 35 and looped around the screw 37, in which position it may be secured, beneath the center contact 38, by tightening the screw 37.

The insulating button 31 is formed with a cavity 39 at one side thereof, into which cavity the metal of the sleeve contact 29 is bent, so as to form a square recess 40 in the sleeve contact. The cavity 39 is larger than the bent-in portion of the sleeve contact 29, so as to provide room for the passage of the lead conductor behind the sleeve contact 29 and over the outer edge of the same. A square nut 41 is placed in the recess 40, and receives a binding screw 42. The second lead wire is passed up into the cavity 39, behind the sleeve contact 29, and is bent over the latter and secured beneath the binding screw 42 (Fig. 6). It will be seen, therefore, that one of the leading-in conductors is in electrical connection with the central contact 38, while the other leading-in conductor is in electrical connection with the sleeve contact 29.

An insulating bushing is threaded into the collar 30, and is of such length that its edge will bind against the lead conductors and force them against the button 31, when the bushing is screwed home into the collar 30. By this means, a conductor grip is provided,

which prevents the leading-in conductors from being torn away from the binding terminals during the use of the device or in case of a sudden pull being imparted to the leading-in conductors. The bushing 43 is formed with a return flange 44 which covers the greater portion of the collar 30, this flange being preferably knurled, so as to facilitate the manipulation thereof when it is desired to introduce or remove the bushing. A washer 45 is inserted between the edge of the flange 44 and the shoulder formed by reducing the collar 30 of the sleeve contact 29.

In the use of the device, the outer member is secured into a wall socket, lamp socket or the like, it being noted that, by reason of the fact that the button 10 can remain stationary with respect to the threaded sleeve 23, the latter rotating upon the button, the outer member will be firmly locked in the socket. Accidental loosening of the outer member thus is prevented. Whenever it is desired to couple up a sadiron, electric fan, or other translating device which is connected to the conductors of the inner member, this is effected by simply pushing the inner member into the outer member. When this is done, the center contact 38 of the inner member makes connection with the center contact 15 of the outer member, the latter being held in contact by reason of its own resiliency aided by that of the spring 16. The sleeve contact 29 makes electrical connection with the sleeve 19 of the outer member, its groove 28 engaging in the bead 27 of the sleeve 19 and serving to secure the inner member detachably in position. All that is necessary, when the inner member is to be withdrawn, is to exercise a pull upon it sufficient to overcome the spring action of the sleeve 19. The button 31 of the inner member, and the sleeve contact 29 are so shaped that the members of the plug will come apart regardless of the direction in which a pull is applied to the inner member. For instance, if the conductors are pulled upon in a direction at an angle to the axis of the plug, the inner member will simply be withdrawn. This is of considerable importance, in that in case of any accident, such as the falling of a sadiron or the like, by which a sudden pull is imparted to the conductors, the only result will be that the members of the plug will be separated. By this means, injury to the plug itself or to the parts of the socket, is avoided.

In separable plugs, as heretofore provided, it was inconvenient to secure the plugs into the socket unless the parts of the plug were separated first, since, in screwing in the plug, the conductor wires became twisted. In the plug described above, this is not the case, the rotatable threaded contact 28 permitting the plug to be held stationary, with

respect to the socket, the threaded contact 23 being rotated alone to effect the insertion of the plug. The plug is simple; and the parts are of such a nature that they may be made by simple stamping and spinning operations, whereby a strong and durable plug may be produced at a low cost.

What I claim as new and desire to secure by Letters Patent is:

- 10 A separable attachment plug comprising two members, one of said members including an insulating base, electrically connected inner and outer center contacts carried by said base, a conducting sleeve secured to said base and extending rearwardly thereof so as to form a chamber, and a threaded outer

contact rotatably mounted on said sleeve, and the other member including an insulating base having a center contact for engagement with said inner center contact and 20 having an outer contact for engagement with said sleeve, said members having interengaging manually releasable means for retaining them together.

In witness whereof, I have hereunto subscribed my name in the presence of two witnesses.

ERNST G. K. ANDERSON.

CHARLES G. COPE,
T. L. TOBIAS.

It is hereby certified that in Letters Patent No. 1,225,391, granted May 8, 1917, upon the application of Ernst G. K. Anderson, of Chicago, Illinois, for an improvement in "Attachment-Plugs," errors appear in the printed specification requiring correction as follows: Page 2, line 35, for the reference-numeral "39*" read 39; same page, line 41, for the reference-numeral "39" read 39*; and that the said Letters Patent should be read with these corrections therein that the same may conform to the record of the case in the Patent Office.

Signed and sealed this 17th day of July, A. D., 1917.

[SEAL.]

F. W. H. CLAY,

Acting Commissioner of Patents.
